(57) **CLAIM**

The ornamental design for an elevated spatula, as shown and described.

DESCRIPTION

FIG. 1 is a side view of an elevated spatula showing my new design; and,

FIG. 2 is a bottom view thereof.

FIGS. 1 and 2 show an elevated spatula with a flat top and a single bump on the bottom side where the head and handle of the elevated spatula are joined.

All surfaces not shown form no part of the claimed design.
